J. P. CONWAY & G. HOFFMAN.
HANGER FOR ELECTRIC CONDUCTORS.
APPLICATION FILED MAR. 12, 1910.

960,827.

Patented June 7, 1910.

UNITED STATES PATENT OFFICE.

JAMES P. CONWAY AND GEORGE HOFFMAN, OF ARNOLD CITY, PENNSYLVANIA.

HANGER FOR ELECTRIC CONDUCTORS.

960,827.

Specification of Letters Patent. Patented June 7, 1910.

Application filed March 12, 1910. Serial No. 548,761.

To all whom it may concern:

Be it known that we, JAMES P. CONWAY and GEORGE HOFFMAN, citizens of the United States of America, residing at Arnold City, 5 in the county of Fayette and State of Pennsylvania, have invented certain new and useful Improvements in Hangers for Electric Conductors, of which the following is a specification, reference being had therein to 10 the accompanying drawing.

This invention relates to hangers for electric conductors, and is particularly adapted for use in connection with mines, where it is desired to provide convenient means for 15 supporting the electric conductor along the roof or walls of the mine.

The invention has for its object to provide a hanger of the type described with means whereby the electric conductor can be 20 quickly and easily engaged with the hanger and securely fastened therein, and from which the electric conductor can be easily and quickly removed when desired.

With the above and other objects in view 25 which will more fully appear as the description proceeds, the invention consists of the novel construction, combination and arrangement of parts hereinafter more fully described and then specifically claimed.

30 In the drawing:—Figure 1 is a view in side elevation of a hanger constructed in accordance with our invention, Fig. 2 is a central vertical sectional view of the same, Fig. 3 is a view in side elevation with the parts detached, Fig. 4 is a central vertical sectional view, partly broken away, showing a modified form of construction, and Fig. 5 is a horizontal sectional view of the spike member of the hanger.

40 To put our invention into practice, we provide an interiorly threaded body or cup member 6 from the closed end of which extends a spike 7, which may be of any desired cross sectional contour, though preferably it is made in the rib form herein shown, since such irregular contour of the spike enables a better grip being obtained in the material into which the spike is forced.

45 The body or cup member in the construction shown in Figs. 1 to 3 receives an exteriorly threaded plug 8, which in this instance, is formed of any suitable insulation. In the plug 8 is fixedly secured in any desired manner the shank 9 of a threaded stem 50 or bolt 10, provided with a kerf or slot 10' extending from the outer end of the bolt in-

wardly throughout the length of the threaded portion of said bolt.

In the construction shown in Fig. 4, the cup member 6 and spike 7 are identical with 61 that above described, but the plug 8' in this construction is made of metal and provided with a central cavity 11, in which is insulation 12 which carries the stem 14 of the bolt 10. The stem 14 of the bolt in this instance is preferably threaded so as to be firmly held in the insulation 12. The threaded portion of the bolt in this construction is slotted in the same manner as the bolt shown in Figs. 1 to 3. 70

In both constructions, the slot 10' receives the shank 15 of a supporting hook 16, the free end of the shank 15 being provided with a T-shaped head 17. The shank of the supporting hook is adapted to slide freely in 75 the slot 10' the hook being supported by a nut 18 threaded on the bolt 10 and on which the head of the hook rests. The lower end of the bolt 10 is provided with a transverse groove 19, adapted to receive an electric 80 conductor 19.

With the parts assembled as shown in Figs. 1 and 2, the electric conductor 19 is placed on the bill of the hook member as shown, and the nut 18 is then screwed 85 upwardly so as to bind the electric conductor between the bill of the hook member and the lower end of the bolt 10 securing the electric conductor firmly in position. Obviously, the loosening of the nut 18 allows 90 the hook member to move away from the bolt so that the electric conductor can be easily removed.

From the foregoing it will be observed that we have devised a simple and inexpensive hanger wherein the use of tie-wires is dispensed with. We not only save the cost of tie-wires, but the time and labor heretofore required to place the wires in position. 95

We reserve the right to press or otherwise mount the insulation upon the slotted bolt, and while we have herein shown and described a specific embodiment of the invention as it has been practiced by us, it will be evident that various changes may 100 be made in the details of construction without departing from the spirit of the invention.

Having fully described our invention, what we claim as new and desire to secure 110 by Letters Patent, is:—

1. A hanger for conductor wires, com-

- prising an interiorly threaded cup member provided on its closed end with a spike, a plug threaded into said cup member, a slotted bolt carried by said plug, a supporting hook mounted in said slot and having a head on its inner end, and a nut on the bolt upon which said head rests.
2. A hanger for conductor wires, comprising a cup member provided on its closed end with a spike, a supporting bolt detachably secured to the cup member and being slotted in the portion projecting beyond the cup member, a supporting hook slideable in the slot of said bolt, and a nut on the bolt for supporting said hook and for moving the same toward the inner end of the bolt.
3. A hanger for conductor wires comprising a cup member provided on the closed end thereof with securing means, a plug threaded into said cup member, a bolt carried by said plug and having a slotted outer end, a supporting hook mounted to slide in the

slotted portion of the bolt, and means on the bolt for retaining the supporting hook in position and for moving the same toward 25 and away from the cup member.

4. A hanger for electric conductors comprising a cup member interiorly threaded and provided on the closed end with a securing spike, a bolt supported from the cup 30 member and insulated therefrom, said bolt provided with a slotted outer portion, a supporting hook movable in the slot of said bolt, and a nut on the bolt supporting said hook and also constituting means to move 35 the hook longitudinally of the bolt.

In testimony whereof we affix our signatures in the presence of two witnesses.

JAMES P. CONWAY.
GEORGE HOFFMAN.
